MERCANDISE PACKAGE

William A. Ringler, Wayne, Pa., assignor to National Folding Box Company, New Haven, Conn., a corporation of New Jersey

Application August 25, 1939, Serial No. 291,801

15 Claims. (Cl. 229—34)

This invention relates to improved merchandise packages, and more particularly to paperboard boxes which may be shipped to the user as flat blanks and thereafter erected as needed to enclose and retain the merchandise, assembly being effected by a simple manipulation of interlocking parts.

In the packaging of numerous articles of merchandise of somewhat bulky nature, substantial savings in shipping and storage costs can be attained if the container which is to enclose the merchandise may be formed from a single flat blank of paperboard material which may be shipped to the user or merchandise manufacturer in flat condition. Further economies in packaging costs may be realized if the blank is so constructed that the merchandise can be placed therein and the blank assembled by a simple manipulation of interlocking parts, to provide a strong, rigid and serviceable merchandise container held together by such interlocking parts without the application of glue, stitches, staples or other applied securing means.

In accordance with this invention, a flat blank is provided comprising a bottom panel, side and end wall panels hinged thereto and side and end flap sections which may be folded inwardly and interlocked together to provide a rigid inwardly extending merchandise-retaining rim or flange. The container-forming blanks may be inexpensively formed by cutting and scoring the same on an automatic cutting and scoring machine from large sheets or rolls of suitable paperboard material fed into the machine. The flat blanks as ejected from the machine may be stacked, packed and shipped to the user or merchandise manufacturer within a limited cubical space.

In one form of the invention the merchandise manufacturer places the merchandise on the bottom panel of the expanded blank, the merchandise being suitably stacked or folded so as to be retained within the contours of the bottom panel. To give additional strength to the container when assembled, the user may place a reinforcing frame upon the bottom panel of the blank and place the merchandise within the reinforcing frame. The reinforcing frame may be formed of suitable corrugated board comprising side and end wall sections suitably hinged together, which sections correspond in size to the side and end wall panels of the blank.

In either form of the invention the side wall panels of the blank are raised to vertical position and the rim-forming sections hinged thereto

are turned inwardly, each side rim section comprising an overlying rim portion and an underlying rim portion which are hingedly connected together. An end tab is hinged to each end of each side wall panel, which tabs are adapted to swing inwardly. The end wall panels are raised so as to overlie the inturned tabs, which tabs may also be provided with flaps which extend inwardly over and in spaced relation to the bottom panel. Each end wall section is provided with an inturned rim section provided with ear portions adapted to be inserted between the overlying and underlying rim portions forming the side rim sections. These ears serve to hold the side and end wall panels of the box in rigid merchandise-containing position.

The inturned rim sections hinged to the side and end wall panels when thus interlocked together provide a substantially continuous rim which retains the merchandise within the box. The various boxes illustrated and described in this application may be made of any desired size to hold any desired quantity or type of merchandise by making the bottom wall panel of the required size and shape and the side and end wall panels of the required height, reinforced, if necessary, to permit vertical stacking. The container may be closed by a cover comprising a flat blank of paperboard material retained in place by the inwardly extending rim of the box. In another embodiment of the invention, a cover panel hinged to the box body is provided, all formed from a single blank of paperboard material. The container and its contents may, if desired, be enclosed within a suitable wrapper, such as transparent Cellophane or decorated sheet material.

Numerous articles of merchandise, such as blankets, bed sheets, bedspreads, curtains, textile materials, confections, and numerous other articles, may be conveniently and effectively packaged in the various boxes forming the subject matter of this invention. The merchandise filled packages may be stacked one upon the other without danger of crushing the box or its contents.

An object of this invention is to provide an improved blank formed from a single piece of paperboard material which may be shipped in flat extended condition to the user and thereafter assembled by the user to provide a strong and rigid container or box for merchandise which is held fixedly and rigidly assembled by its interlocking parts without glue, staples, stitches, or other applied securing means.

Another object of this invention is to provide an improved merchandising package comprising a folded blank so constructed that it may be wrapped around the merchandise positioned on the bottom panel thereof to form a rigid and highly serviceable container held in assembled position by easily manipulated interlocking parts.

Another object of this invention is to provide an improved merchandise container formed from a single blank of paperboard material comprising bottom, side and end wall panels and an in-turned merchandise retaining rim held together by easily and quickly manipulated interlocking parts.

Another object of this invention is to provide an improved merchandise container which can be economically formed from a single blank of paperboard material, which blank may be shipped to the user in flat extended condition, which may be quickly and easily assembled to enclose and retain the merchandise by a few simple operations performed during the packaging of the merchandise, which provides a strong, attractive and highly serviceable container in which the merchandise may be shipped to, stored by and displayed by the merchant.

Various other features and advantages of the invention will be apparent from the following particular description and from an inspection of the accompanying drawings.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which:

Fig. 1 is a plan view of a prepared blank which has been cut and scored to form when erected my improved box;

Fig. 2 is a perspective view of the blank shown in Fig. 1 as it appears when partially erected into merchandise-containing position;

Fig. 3 is a fragmentary perspective view of the box-forming blank as it appears at a further stage of erection into box form;

Fig. 4 is a perspective view of the box showing one end thereof fully erected into box form and the other end thereof partially erected;

Fig. 5 is a cross-sectional view of the fully erected box with merchandise, such as a blanket packed therein, this view showing the packed box as it would appear when looking in the direction of the arrows 5-5 of Fig. 4;

Fig. 6 is a plan view of a prepared blank suitably cut and scored to provide when erected a box of somewhat modified construction;

Fig. 7 is a plan view of a prepared blank which has been suitably cut and scored to provide a cover for the erected box;

Fig. 8 is a perspective view of the blank shown in Fig. 6 in the process of erection around a frame insert which provides a stiffener for the side and end walls of the erected box;

Fig. 9 is a perspective view of the blank as it appears at a further stage of erection around the stiffener frame;

Fig. 10 is a perspective view of the fully assembled box formed from the blank shown in Fig. 6, erected to enclose the stiffener frame;

Fig. 11 is a top plan view of the box shown in Fig. 10 showing the cover member illustrated in Fig. 7 in position to close the open top of

the box, the cover member being shown in dotted lines so that the construction of the box will be more readily apparent;

Fig. 12 is a perspective view of the erected box having merchandise packed therein, this view showing the cover member in process of being applied to the packed box;

Fig. 13 is a cross-sectional view through the packed box showing the cover member in place and as it would appear when looking in the direction of the arrows 13-13 of Fig. 14;

Fig. 14 is a perspective view of the packed box showing the cover member undergoing removal to give access to the contents;

Fig. 15 is a plan view of a prepared blank which has been suitably cut and scored to provide a merchandise box of further modified construction;

Fig. 16 is a perspective view of the blank shown in Fig. 15 undergoing erection;

Fig. 17 is a perspective view of the blank shown in Fig. 15 as it appears at a further stage of erection;

Fig. 18 is a perspective view of the box as it appears at the final stage of the erecting operation, this view showing certain locking parts thereof in the process of being swung into position to retain the box in rigid erected form;

Fig. 19 is a cross-sectional view through the erected box as it would appear when looking in the direction of the arrows 19-19 of Fig. 18;

Fig. 20 is a plan view of a prepared blank which has been suitably cut and scored to provide a box of further modified construction equipped with a cover closure formed integral with the box-forming portion of the blank;

Fig. 21 is a perspective view of the blank shown in Fig. 20 as it appears at one stage of erection into box form;

Fig. 22 is a perspective view of the blank as it appears at a further stage of erection into box form;

Fig. 23 is a perspective view of the blank as it appears at a still further stage of erection into box form;

Fig. 24 is a perspective view of the blank as it appears in its final stage of erection into box form; and

Fig. 25 is a cross-sectional view of the fully assembled box with the cover portion swung into closed position and as it would appear when looking in the direction of the arrows 25-25 of Fig. 24.

Similar reference characters refer to similar parts throughout the several views of the drawings and the specification.

The box as shown in Figs. 4 and 5 may be assembled from the blank shown in Fig. 1, which blank can be prepared by cutting same to the proper shape and scoring same on an automatic cutting and scoring machine. Large sheets or rolls of suitable paperboard material are fed into the cutting and scoring machine which operates to score the blanks and cut the blanks therefrom automatically and at high production speed. A large number of blanks, each of which has been cut and scored as shown in Fig. 1, may be arranged in stacked relationship so as to occupy a minimum of cubic space, which blanks may be packed in suitable packing cases and shipped to the user to be erected as needed.

The blank as shown in Fig. 1 comprises a bottom wall panel 1 having side wall panels 2 hinged to the bottom wall panel along the fold or score lines 3, and end wall panels 4 hinged to the bot-

tom wall panel 1 along the fold or score lines 5. Each side wall panel 2 is provided with an in-turned rim-forming section 6 hinged to the side wall panel 2 along the fold line 7. Each rim-forming section 6 comprises a rim-forming portion 6a and a rim-forming portion 6b hinged to the rim-forming portion 6a along the fold line 8. When the box is erected, rim-forming portion 6b is arranged to underlie the rim-forming portion 6a, as will be presently described. A platform portion 6c comprising a generally triangular-shaped portion extends from each end and is formed as an integral part of the underlying rim-forming portion 6b, each triangular portion 6c being defined by a diagonally extending cut line 8c which extends from one end of the fold line 8 to the adjacent end of fold line 7. Thus it is seen that each platform portion 6c is cut free of rim portion 6a and that rim portion 6b is connected to rim portion 6a by the fold line 8 only.

An end wall tab 10 is hinged to each end of each side wall panel 2 along fold line 5', the end tabs 10 being turned inwardly when the box is erected. Each end tab 10 is provided with a flap 11 hinged thereto along fold line 12, which flap is adapted to overlie the bottom wall panel 1 in spaced relationship thereto when the box is erected. The score lines 5' are slightly out of alignment with score lines 5 so as to permit the lower free edge of each end tab 10 to lie within the adjacent fold line 5 so that the adjacent end wall panels 4 may be conveniently erected to lie over the adjacent end tabs 10.

Each end wall panel 4 is provided with a rim-forming section 13 hinged thereto along the score line 14, each section 13 being turned in so as to overlie the bottom wall panel 1 in spaced relationship thereto when the box is erected. Each rim section 13 is provided with an ear portion 13a projecting from each end thereof to provide locking means for retaining the box in rigid erect position. A cover-supporting flap positioned between the ear portions 13a is hinged to each rim section 13 along the fold line 16 to support the adjacent ends of a cover-forming blank. The cover-supporting flap 15 hinged to each rim section 13 may comprise an underlying fold-in portion 15a and a return bend portion 15b hinged thereto along the fold line 17.

In erecting the blank into box form, the user stacks or arranges the merchandise M upon the bottom wall panel 1 of the blank with the side and end edges of the merchandise confined within the fold lines 3 and 5. The rim portions 6b at each side of the blank are folded over the adjacent rim portions 6a. The side wall panels 2 are then erected substantially perpendicular to the bottom wall panel 1, as shown in Fig. 2, with each side rim section 6 folded inwardly so as to extend substantially parallel to the bottom wall panel and in spaced relationship thereto. Each end tab 10 is then swung inwardly so as to extend along the adjacent fold line 5, and each flap 11 is folded at right angles to the end tab 10 to which it is hinged. The corner portion 11a of each flap 11 is arranged to rest upon the adjacent platform portion 6c and is inserted under the adjacent mitered ends 9 of the side rim portion 6a, as illustrated in Fig. 2.

When this operation has been completed, the end wall panels 4 are erected so as to overlie the adjacent end tabs 10 and the ear portions 13a thereof are swung into position to overlie the adjacent flaps 11 with the ends thereof inserted un-

der the adjacent mitered ends 9 of the side rim portion 6a, as illustrated more particularly in Figs. 3 and 4. The ear portions 13a are frictionally gripped between the overlying side rim portions 6a and the underlying side rim portions 6b, so that the box when thus erected is held in rigid erected assembly.

The box may be left open at the top thereof, if desired, to permit ready inspection of the merchandise therein, or the box may be enclosed in a wrapper sheet, such as transparent Cellophane or a decorated paper wrapper. If a closure cover for the box is desired, each end rim section 13 may be provided with a cover-supporting flap 15 hinged thereto. Prior to the application of the cover, portion 15a of the cover-supporting flap may be folded around the inner edge of the aligned flaps 11, as shown more particularly in Fig. 5, so as to lie against the inside face of flaps 11. Portion 15b is then rebent so as to underlie the adjacent portion 15a, portion 15b then providing a shelf support for the cover closure 25 which may rest against the top of the merchandise, as shown in Fig. 5.

The cover closure may comprise a flat blank of paperboard material which is of sufficient size to be inserted under the inturned side rim sections 6a with the ends thereof inserted between the adjacent cover-supporting portions 15a and 15b. To facilitate insertion and removal of the cover member, the same may be constructed and formed as shown in Fig. 7, which cover member will be presently described.

The erected box as shown in Figs. 4 and 5, formed from the single blank of paperboard material as shown in Fig. 1, is thus held together entirely by the interlocking parts thereof, without the use of glue, staples, stitches, or other extraneously applied securing means. The end walls of the box are substantially of double-ply construction, comprising the end tabs 10 and the end wall panels 4, providing a rigid and strong construction so that a large number of packed boxes may be stacked one upon the other without crushing. The inturned rim flaps 10, against which the inwardly extending ends of the triangular platform 6c abut, maintain the underlying rim portions 6b substantially in parallelism with the overlying rim portions 6a. The side rim sections 6 and the end rim sections 13 provide a substantially continuous merchandise-retaining rim around the top of the box, which is rigidly supported by the interlocking parts so as to maintain a rigid inturned position. The erected box cannot be disassembled or pulled apart by force without actually tearing the paperboard unless a specific unlocking procedure, which is the reverse of the erecting procedure, is followed. The box as completed is neat and attractive in appearance, presents no raw or rough edges, and provides a highly satisfactory box which can be quickly and expeditiously erected by the user without tools or machinery, to provide a highly serviceable box for numerous articles of merchandise.

A box of somewhat modified construction as illustrated in Figs. 10 to 14 inclusive, may be assembled from a prepared blank of paperboard material as shown in Fig. 6. This blank comprises a bottom wall panel 1 having side wall panels 2 hinged to the opposite sides of the bottom wall panel 1 along fold or score lines 3, and end wall panels 4 hinged to the opposite ends of bottom wall panel 1 along fold or score lines 5. A merchandise-retaining rim section 6 is hinged

to each of the side wall panels 2 along a fold line 1, each side rim section 6 comprising an overlying rim portion 6a and an underlying rim portion 6b hinged thereto along the fold line 8.

The adjacent ends of the end wall panels 4 and the side wall panels 2 are connected by means of bellows fold portions, each portion comprising a bellows fold section 20 hinged to the side wall panel 2 along fold line 5' and bellows fold section 23 hinged to the adjacent end of end wall panel 4 along fold line 3', bellows sections 20 and 23 being connected together by diagonally extending fold line 24 which extends diagonally from the point of intersection of the adjacent fold lines 3 and 5. A cut line 25 extending generally parallel to the fold line 3' intersects the diagonally extending fold line 24, and partially separates bellows section 20 from bellows section 23. It will be noted that the end of bellows section 20 extends a distance beyond the free edge of bellows section 23 and that each bellows section 20 is provided with an inturned flap 21 hinged thereto along the fold line 22. It will also be noted that the paired fold lines 5' are slightly closer together than fold lines 5, so as to permit proper folding of the bellows section 20 and 23. Score lines 3' may be, however, in direct alignment with score lines 3.

Each end wall panel 4 is provided with a rim-forming section 13 hinged thereto along the fold line 14. Each rim section 13 is provided with a projecting ear portion 13a extending from each end thereof to provide means for locking the blank in erect box-forming position. Each rim section 13 may also be provided with a locking flap 15' spaced between the ear portions 13a and hinged to the rim section 13 along fold line 17.

If merchandise of substantial weight or volumetric size is to be packed in the box assembled from the blank shown in Fig. 6, it may be desirable to provide a stiffening frame 30, as shown in Fig. 8, around which the side and end wall panels may be wrapped. This frame member 30 may be formed from relatively stiff cardboard, such as corrugated boxboard, having opposed side sections 32 and opposed end sections 31 suitably connected together at the corners. The frame member may be conveniently formed from a single strip of boxboard, which is transversely scored at three places to define the side and end sections, the meeting ends of the strip being secured together by a suitable corner stay. The frame member 30 may be of such size that the outside faces thereof coincide with the inside edge of the score lines 3 and 5 of the box-forming blank.

When the merchandise is to be packaged, the frame member 30 is placed in position upon the bottom wall panel 1 of the blank and the merchandise packed within the frame member 30 supported upon the bottom wall panel 1. Each side rim portion 6b is then folded to overlie the adjacent side rim portion 6a. A flange portion 27 hinged to each rim portion 6b along fold line 28 may be provided which overlies the inside face of side wall panel 2 when rim portion 6b is folded to overlie rim portion 6a. Each side wall panel 2 is raised so that the underlying rim portion 6b will overlie the adjacent top edge of the adjacent side section 32 of the frame, with the flange portion 27 positioned between the outside face of the adjacent side section 32 of the frame and the inside face of the adjacent side wall panel 2 of the blank.

Bellows section 20 is then swung into parallel-

ism with the adjacent end section 31 of the frame so as to overlie the outside face thereof. The corner portion 21a of each flap 21 is then turned inwardly so as to overlie corner portion 6b' of rim portion 6b and is inserted under the mitered edge 26 of overlying rim portion 6a, as shown more particularly in Fig. 9. As thus arranged it will be noted that each end section 31 of the frame provides a support for the adjacent bellows section 20 and inturned flap 21.

The end wall panels 4 are then raised into vertical position and bellows portion 23 hinged to each end thereof is swung inwardly so as to overlie the outside face of the adjacent bellows sections 20, as shown more particularly in Fig. 9. When erected, the end wall panels 4 will closely overlie the outside face of adjacent end section 31 of the frame and the outside face of adjacent bellows sections 20. As the end wall panels 4 are raised into position, rim section 13 is turned inwardly and the ear portions 13a thereof are inserted so as to overlie the ends 21a of the adjacent flaps 21 and extend under the mitered edge 26 of the rim portions 6a, in the manner shown in Fig. 10. The friction exerted upon the ear portions 13a by the overlying rim portions 6a and the underlying rim portions 6b prevents withdrawal of the ear portions and retains the box in rigid assembled position. It will here be noted that rim portions 6a and 6b are held squeezed together by reason of the fact that both extend over the top edge of the adjacent side sections 32 of the frame, the side sections 32 and end sections 31 of the frame being of such height with respect to side wall panels 2 and end wall panels 4 of the blank as to effect this result.

The locking flap 15' hinged to each end rim section 13 may be turned inwardly around the inner edge of aligned end flaps 21 so that the free edge 21a thereof will overlie the top edge of the adjacent end section 31 of the frame, as shown more particularly in Fig. 13, thus locking the flap 15 in fixed position.

The box is thus assembled in rigid container form without the use of glue, staples, stitches or other applied securing means and is held together solely by the interlocking frictional engagement of the parts thereof. By the provision of a frame within the box-forming blank a box is provided which has unusually stiff and rigid side and end walls so as to support merchandise of substantial size and weight, permitting numerous boxes to be stacked one upon the other without danger that the merchandise in the boxes or the boxes themselves will be crushed by the superimposed weight. The box is especially adapted for the packaging of bulky articles of merchandise, such as blankets, sheets and pillow cases. The blank can be erected after the merchandise has been placed upon the bottom panel of the blank without requiring a pre-assembled box which would occupy valuable storage and shipping space. The side rim sections 6 and end rim sections 13 when assembled into box form provide a substantially continuous rim which is unusually strong and rigid, and which serves to retain the merchandise in the box so that the merchandise cannot easily be removed from the box without tearing or disassembling the blank.

If desired, a cover 35, such as shown in Fig. 7, may be provided to close the open top of the box. The cover member 35 is formed from a single blank of paperboard material and so constructed that it can be easily inserted into box-closing

position and easily removed therefrom to permit inspection of the merchandise. The cover 35 comprises a substantially rectangular blank of paperboard material having mitered corners 36, comprising a covering portion 37, and side edge portions indicated at 38 which are inserted under the inturned side rim sections 6 and positioned to overlie the merchandise M. To effect insertion of the end portions 39 of the cover blank, a pair of parallel extending fold lines 40 and 41 are provided which define fold portions 42 and 43. A pair of ears 44, each defined by an arcuate cut line 45 which extend into the covering portion 37 of the blank, provides means by which the cover blank may be manipulated.

It will be appreciated that to effect insertion of the side edge portions 38 under the side rim sections 6, the top portion 37 of the blank must be bowed convexly, as shown in Fig. 12, which would normally be prevented when the end portions 39 are folded downwardly at right angles to the top portion 37. Bowing of the top portion 37 is effected in my improved cover blank by the provision of parallel extending fold lines 46, which fold lines extend transversely through the fold portions 42 and 43 to the ends of the arcuate cut line 45. A pair of diagonally extending fold lines 47 is provided, each extending from the meeting point of arcuate cut line 45 with score line 40 and extending diagonally across fold portions 42 and 43. Each diagonally extending fold line 47 and the adjacent transverse score line 46 define a triangular-shaped section 48 therebetween which permits the section 49 between the parallel extending fold lines 46 to be swung inwardly so that the fold portions 42 and 43 exterior to the diagonally extending fold lines 47 may be swung into position substantially at right angles to the top portion 37 of the blank irrespective of the amount which the top portion 37 is bowed or convexed. When the top section 37 is bowed, the tabs 44 will project upwardly and will permit the insertion of the end portions 39 into the box over the edge of the adjacent end rim section 13. When inward pressure on the end portions 39 is released, the end portions 39 will swing outwardly underneath the overlying end rim sections 13. The top portion 37 as well as the side portions 38 and end portions 39 thereof will then spring in a substantially flat plane, as shown in Fig. 13, so as to overlie the merchandise and protect the same from dust and contamination.

It will be appreciated that the assembled box, as shown in Figs. 11 and 13, may be enclosed in a suitable wrapper which may or may not be made of transparent material, with or without the provision of the cover panel 35. The cover panel 35, however, provides a convenient closure, which can be easily removed to permit inspection of the contents, which can be effected by exerting an upward pull on the tabs 44. The cover panel 35 might also be used to close the open top of the box shown in Fig. 4. If desired, a stiffening frame 30 may also be provided in the box shown in Fig. 4, to stiffen and strengthen the side and end wall panels thereof.

A further modified form of merchandise box is shown in Fig. 18, which may be formed from a single blank of paperboard material as shown in Fig. 15, held together in rigid box assembled form solely by interlocking parts without the use of stitches, staples, adhesive, or other applied securing means. The box-forming blank as shown in Fig. 15 comprises a bottom wall panel 1 having

5 side wall panels 2 hinged to the bottom wall panel along fold lines 3 and end wall panels 4 hinged to the bottom panel along fold lines 5. An inturned rim-forming section 6 is hinged to each of the side wall panels 2 along the fold line 7, each rim section comprising an overlying rim portion 6a having the ends 26 thereof cut on a miter, and underlying rim portion 6b hinged to rim portion 6a along fold line 8. A supporting flap 58 hinged to rim portion 6b along fold line 59 may also be provided.

An end tab 10 is hinged to each end of each side wall panel 2 along fold lines 5' and is provided with an inturned flap 11 hinged to the tab 10 along fold line 12. The fold lines 5' defining the ends of each of the side wall panels 2 are spaced slightly closer together than the parallel extending fold lines 5, so as to permit each of the end tabs 10 to fold inwardly so as to lie just within the adjacent fold lines 5.

15 Each end wall panel 4 has a rim section 13 hinged thereto along fold line 14, which rim section is provided with a projecting ear portion 13a at each end thereof. There is further provided a rim-supporting section comprising the rim portion 52 hinged to rim section 13 along the fold line 53 and a supporting portion 54 hinged to rim portion 52 along fold line 55. The ear portions 13a are each defined by an arcuate-shaped cut line 51, the inner ends of the cut lines 51 extending to the fold line 53. To facilitate insertion of the rim-supporting section into the box, a pair of parallel extending fold lines 57 are preferably provided, which extend from fold line 53 outwardly through the rim portion 52 and supporting portion 54.

20 In assembling the box from the blank shown in Fig. 15, each rim portion 6b of each side rim section 6 is folded to overlie its adjacent rim portion 6a, which folding operation places supporting portion 58 in position to overlie the inside face of the adjacent side wall panel 2. Each side wall panel 2 is then raised to substantially vertical position, as shown in Fig. 16, with each rim section 6 extending inwardly. Supporting portion 58 is of such height as to maintain the rim portion 6b closely seated against the inside face of the overlying rim portion 6a. Each of the end tabs 10 is then swung inwardly and the flap 11 hinged thereto is folded substantially at right angles to its end tab 10 so as to permit the corner portion 11a of the flap to be positioned to overlie a projecting corner portion 6b' of the underlying rim portion 6b and to be inserted beneath the overlying rim portion 6a under the mitered edge 26 thereof.

25 Each of the end wall panels 4 is then raised, its associated rim section 13 folded inwardly, and the ear portions 13a are inserted under the mitered ends 26 of the adjacent overlying rim portion 6a, which operation brings the end wall panels 4 into a position at right angles to bottom wall panel 1, as shown in Fig. 18. Each rim portion 52 hinged to each of the rim sections 13 is then folded over the inner edges of the aligned flaps 11 so as to underlie the inside face of these flaps, which operation is permitted by reason of the fact that the end portions 56 of the rim-supporting section will fold so as to swing past the inner edges of the adjacent side rim section 6, as shown more particularly in Fig. 18. When rim portion 52 has been swung under the adjacent flaps 11 so as to abut the inside face thereof, supporting portion 54 may then be pushed outwardly 30 so as to abut the inside face of the adjacent end

wall panel 4. When in this position the end portions 56 of the supporting section are free to expand outwardly so as to lie substantially in the same plane and in abutting position against the inside face of the adjacent end wall panel 4, as shown in Fig. 19. The lower edge of each of the supporting portions 54 rests against the inside face of the bottom wall panel 1 and retains its associated rim portion 52 in closed abutment against the inside face of its associated rim section 13.

The box as thus constructed and erected presents substantially double-ply side and end walls, the double-ply side walls being formed by the side wall panels 2 and the supporting portions 58, and the end panels being formed by the end wall panels 4 and the supporting portions 54. The end tabs 10 provide further stiffening support of the end walls of the box. A box is thus provided which will stand up under substantial superimposed pressures so that a large number of packed boxes may be stacked one upon the other. In this form of box the merchandise may be most conveniently packed in the box after the box has been completely erected, since the merchandise might interfere with the proper infolding of the rim portions 52 and the supporting portions 54. The side rim sections 6 and the end rim sections 13 provide a substantially continuous rim which assists in retaining the merchandise within the box and which provides an attractive framing for the merchandise packed therein. The assembled box with the merchandise packed therein may be enclosed in a suitable wrapper or the open top thereof may be closed by a suitable paperboard cover blank tucked under the rim-forming sections 6 and 13, which cover-forming blank may be constructed as illustrated in Fig. 7.

In the packaging of certain types of merchandise it may be desirable to provide a box with a hinged cover. There is shown in Figs. 24 and 25 an attractive box for merchandise having a hinged cover associated therewith, which is formed entirely from a single blank of paperboard material, as illustrated in Fig. 20. This box-forming blank comprises a bottom wall panel 1 having side wall panels 2 hinged to bottom wall panel 1 along fold lines 3 and end wall panels 4 hinged to bottom wall panel 1 along fold lines 5. Each of the side wall panels 2 is provided with a rim-forming section 6 hinged thereto along a fold line 7, each rim section comprising a rim portion 6a having mitered ends 26 and a rim portion 6b hinged to rim portion 6a along fold lines 8. A reenforcing flap 80 having mitered ends 81 hinged to rim portion 6b may be provided to strengthen and stiffen the construction. Each of the side wall panels 2 may be provided with an end wall tab 10 hinged to one end thereof along fold lines 5', each tab 10 being provided with an inturned flap 11 hinged thereto along fold line 12.

A front wall panel 4 hinged to the bottom wall panel 1 along fold line 5 is provided with a rim-forming section 13 hinged to the front wall panel along the fold line 14. The rim-forming section 13 is provided with an ear portion 13a at each end thereof each defined by an arcuate cut line 51 which intersects a fold line 53 by means of which a rim-supporting section is hinged. The rim-supporting section comprises a rim portion 52 joined to the rim section 13 by fold line 53 and a supporting portion 54 hinged to the rim portion 52 by fold line 55.

The end portions 56 of the rim-supporting section are defined by a pair of parallel score lines 57 which extend transversely across rim portion 52 and supporting portion 54, terminating at the fold line 16.

The primary rear wall of the box body is formed by a pair of end tabs 70 hinged to the rear end of each of the side wall panels 2 along fold line 5', the tabs 70 being of sufficient length 10 to meet and preferably overlap, to provide a substantially continuous rear wall. One of the tabs 70 may be longer than the other tab 70, which increased length is indicated by end extension 70'. Each of the end tabs 70 is provided with a primary rim-forming section comprising rim portion 71 hinged to the tab 70 along the fold line 72 and rim portion 73 hinged to rim portion 71 along fold line 74. A stiffening flap 75 having mitered ends 77 may be hinged to each of the rim portions 73 along fold line 78. One of the rim portions 73 may be provided with an ear extension 79 hinged to the inturned end thereof along fold line 79, for a purpose which will presently appear.

A secondary rear wall panel 61 which may have a slightly greater height than the front wall panel 4 to provide a bulged book back effect, is hinged to the rear edge of the bottom wall panel 1 along the fold line 5. A secondary rim-forming section 63 is hinged to the secondary rear wall panel 61 along the fold line 62. A cover panel 60 is hinged to the secondary rim-forming section 63 along fold line 64. The secondary rim-forming section 63 may be provided 30 with an ear portion 63a at each end thereof, which are formed by the miter cut lines 65 which intersect the cover hinge line 64. A locking tab 66 may be hinged to the free edge of the cover panel 60 along fold lines 67, locking tab 66 having a locking flap 68 hinged thereto along fold line 69 which is adapted to be inserted 40 through the slit or cut 84 provided in the lower edge of front wall panel 4 adjacent the score line 5.

In assembling the box, a strip of adhesive *g* 45 may be applied to the inside face of each of the rim portion flaps 75 and 80, which may be economically and quickly applied by means of a strip gluing machine. Each rim portion 6a is folded over the adjacent rim portion 6a to which it is hinged and reenforcing flap 80 pressed into adhesive engagement with the inside face of the adjacent end wall panel 2. Similarly, rim portion 73 is folded over rim portion 71 and reenforcing flap 75 pressed into adhesive engagement 50 with the inside face of the end tab 70, producing an assembly as illustrated in Fig. 21. It will be appreciated that, if desired, the adhesive *g* applied to the reenforcing flaps 80 and 75 may be eliminated, and these reenforcing flaps increased in height so as to substantially 55 equal the height of the adjacent end wall panel 2 and the adjacent end tab 70, so that when the parts are erected the free edge of the reenforcing flaps 80 and 75 will rest against the inside face of the bottom wall panel 1.

Side wall panels 2 are then erected into substantially vertical position, as shown in Fig. 22, flaps 11 are folded to extend substantially at right angles to the erected end tabs 10, and the corner portion 11a of each flap 11 is tucked under the mitered edge 26 of the overlying side rim portion 6a, which operation places the end tabs 10 substantially in alignment with the low- 70 75

er edge resting upon the bottom wall panel 1 adjacent the fold line 5.

At this point, if desired, the front wall of the box may be erected in secured position by erecting the front wall panel 4 and inserting the ear portions 13a under the mitered ends 26 of the overlying side rim portions 6a, as illustrated in Figs. 22 and 24, which insertion operation places the front rim section 13 in position to overlie the inturned flaps 11. Rim portion 52 may then be swung around the inner edge of aligned flaps 11 and swung outwardly so as to lie against the inside face of the flaps 11. This operation can be readily performed by reason of the fact that the hinged end portions 56 of the supporting section will fold over the inner edges of the side flap sections 6. Supporting portion 54 is then pressed against the inside face of front wall panel 4 and end portions 56 will expand outwardly by reason of the resilient nature of the paperboard so as also to lie flat against the inside face of the front wall panel 4.

The rear wall panel of the box may then be erected and secured in fixed position by swinging the end tabs 70 inwardly into alignment so that the lower edge thereof rests upon the rear edge of bottom wall panel 1 adjacent fold line 5. In this position the end extensions 70' of one of the end tabs 70 will overlap the free end of the other end tab 70, as shown in Fig. 22. Simultaneously with this folding operation the corner portions 71a of the rim sections forming a part of the end tabs 70 are inserted under the adjacent mitered edges 26 of the side rim portions 6a so as to rest upon the projecting ends 6b' of the side rim portions 6b, as illustrated in Fig. 22. The ear portion 78 hinged to one of the rim portions 71 is then inserted between the overlying rim portion 71 and the underlying rim portion 73 hinged to the opposite end tab, the insert 78 thus serving as a splicing element to retain the end tabs 70 in overlapping alignment and retain the ends of the primary rim sections hinged to the tabs 70 in fixed substantially abutting relationship, as illustrated in Fig. 23.

The secondary rear wall panel, 61, which may be in the form of a book back, if desired, is then raised into vertical position and the ears 63a forming a part of the secondary rim section 63 are inserted under the adjacent mitered edges 26 of the overlying side rim portions 6a, as illustrated more particularly in Figs. 22 and 24. When thus inserted, the secondary rim section 63 will provide a smooth and finished rear edge for the box. Thus the front rim section 13 is supported and reenforced by rim portion 52 and supporting portion 54, the side rim sections 6a comprising the overlying rim portions 6a and the underlying rim portions 6b, are supported and reenforced by the reenforcing flaps 80, and the primary rim sections formed by the overlying rim portions 71 and the underlying rim portions 73 are reenforced by flaps 75, which primary rim sections further support and reinforce the secondary rear wall rim section 63. The box body as thus constructed is provided with double-ply side, front and rear walls, so that numerous boxes may be stacked one upon the other without danger that the lowermost box will be crushed or the merchandise damaged.

When the box has been thus assembled, the merchandise, such as candies, confections, or numerous other articles, may be packed therein. When the merchandise has been packed within the box, the cover panel 60 is swung down so as

to overlie the side rim sections 6 and the front rim section 13. The cover may be locked into closed position by inserting the locking flap 68 through the cut or slit 84 adjacent the bottom edge of the front wall panel 4. The front wall supporting portion 54 may be provided with a cut-out 85 in the lower edge thereof to permit insertion of the locking flap 68 into the box so as to overlie the inside face of the bottom wall panel 1 thereof, as shown in Fig. 25. As thus arranged, the strap portion 66 overlies the outside face of the front wall panel 4, as shown in Fig. 25.

The box shown in Figs. 24 and 25 can be formed entirely from a single blank of paper-board material as shown in Fig. 20, economically and at low cost. The box-forming blank can be shipped flat to the user and may be stacked, shipped and stored in a minimum of space. When merchandise is to be packed therein, the boxes can be erected by the user as needed. As above explained, the reenforcing flaps 80 and 75 may be made of a height corresponding to the height of the side wall panels 2 and end tabs 70 respectively, so that the lower edge thereof will rest against the bottom wall panel 1 of the box so that no adhesive need be applied thereto. If the reenforcing flaps 80 and 75 are made of shorter height, as shown in Fig. 20, a strip of adhesive may be quickly applied thereto by an automatic strip gluing machine, and these flaps folded and pressed into adhesive engagement with the inside face of the end wall panel 2 and the end tabs 70 to which they are hingedly connected. As thus assembled, the box may be shipped to the user in substantially flat condition, in the form illustrated in Fig. 21. No adhesive, staples, stitches, or other extraneously applied securing means need be applied by the user to erect the box into container form. The erected box presents an unusually attractive and eye-appealing package in which candies, nuts, confections, textiles, wearing apparel, and numerous other articles of merchandise may be conveniently packed. The hinged cover panel protects the contents from contamination and injury, and the boxes may be stacked one upon the other without damage to the contents or danger of crushing.

It will now be seen that I have provided a number of attractive merchandise-containing boxes, all of which may be produced economically and at a high production rate on an automatic cutting and scoring machine, to provide blanks which may be shipped to and stored by the user in flat expanded position, effecting substantial economies in shipping and storage costs. These boxes may all be assembled by the user without the application of glue, staples, stitches or other applied securing means, the boxes being held in rigid merchandise-supporting and containing position entirely by interlocking parts, which may be quickly interconnected. The boxes further provide substantially continuous merchandise-retaining rims which assist in retaining the merchandise within the boxes, which rims further provide an attractive and decorative framing for the merchandise packed therein. The side and end walls of the box are amply reinforced to resist crushing, so that the boxes will adequately withstand severe handling and abuse incident to the shipment, stacking, storage and display of packaged goods. The boxes herein disclosed are especially desirable where bulky merchandise or merchandise occupying substan-

tial cubical space is to be packaged. No assembling machinery is required by the user to erect the box from the flat blank into rigid container form, and in some of the boxes illustrated merchandise can be conveniently placed upon the bottom wall panel of the expanded blank and the blank then erected into container-forming position around the merchandise at no greater expenditure of time than would be required to package the merchandise in a fully set up box.

My improved box is formed from a one-piece blank comprising a bottom wall panel and enclosing panels hingedly connected thereto, which enclosing panels have been variously referred to as side wall panels and end wall panels to facilitate description. It will be understood that the term "side wall panels" and "end wall panels" as used herein are not intended to designate either the relative lengths or heights of the enclosing panel walls, and that essentially alternate panels are provided with double-ply rim-forming sections between which the projecting ears associated with the rim sections connected to the intermediate panels are inserted.

While certain novel features of the invention have been disclosed and are pointed out in the annexed claims, it will be understood that various omissions, substitutions and changes may be made by those skilled in the art without departing from the spirit of the invention.

What is claimed is:

1. A merchandising box formed from a single blank of paperboard material including, a bottom wall panel, oppositely arranged side wall panels hinged to said bottom wall panel, oppositely arranged end wall panels hinged to said bottom wall panel, a rim section hinged to each of said side wall panels comprising hingedly connected overlying and underlying rim portions, an inturned end tab hinged to each end of each side wall panel, an inturned rim flap hinged to each of said tabs, each of said rim flaps having a corner portion thereof inserted between adjacent overlying and underlying rim portions, a rim section hinged to each of said end wall panels folded over adjacent aligned flaps, and interengaging means comprising parts of said rim sections for retaining said box in fixed assembled position.

2. A merchandising box formed from a single blank of paperboard material including, a bottom wall panel, side wall panels hinged to said bottom wall panel, end wall panels hinged to said bottom wall panel, an inturned end tab hinged to each end of each side wall panel, an inturned rim-forming flap hinged to each of said end tabs, a double-ply rim section hinged to each of said side wall panels, each of said rim flaps having a corner portion thereof inserted between the plies of the adjacent double-ply rim sections, a rim section hinged to each of said end wall panels, and interengaging means comprising parts of said rim sections for retaining said box in assembled position.

3. A merchandising box including, a bottom wall panel, a plurality of enclosing panels comprising alternate and intermediate panels hinged to said bottom wall panel, a rigid reinforcing frame supported by said bottom wall panel positioned within said enclosing panels, a double-ply inturned rim section hingedly connected to each of said alternate enclosing panels resting upon the top edge of said frame, said rim sections each having an end extension projecting from the lower ply thereof beyond the ends of the as-

sociated overlying ply, a double-ply inturned rim section hinged to each of said intermediate panels resting on said end extensions and the top edge of said frame, and an ear extending from each end of each intermediate rim section projecting between the adjacent ends of said double-ply rim sections for retaining said rim sections in fixed assembled position.

4. A merchandising box including, a bottom wall panel, a plurality of enclosing panels comprising alternate and intermediate panels hinged to said bottom wall panel, an inturned end tab hingedly connected to each end of alternate enclosing panels, an inturned rim section hingedly connected to each of said alternate panels comprising an overlying rim portion and an underlying rim portion, an inturned rim flap hinged to each of said end tabs having a corner portion thereof inserted between adjacent overlying and underlying rim portions, a rim section including an overlying rim portion hinged to each of said intermediate panels and overlying the adjacent flaps, and an ear portion projecting from each end of said intermediate overlying rim portions frictionally retained between the adjacent overlying and underlying rim portions of the alternate sections.

5. A merchandising box including, a bottom wall panel, a plurality of enclosing panels comprising alternate and intermediate panels hinged to said bottom wall panel, an inturned end tab hingedly connected to each end of alternate enclosing panels, an inturned rim section hingedly connected to each of said alternate panels providing an overlying rim portion and an underlying rim portion, a supporting portion hinged to each of said underlying rim portions for maintaining the overlying and underlying rim portions in substantial parallelism, an inturned rim flap hinged to each of said end tabs having a corner portion thereof inserted between the overlying and underlying rim portions, a rim section hinged to each of said intermediate panels overlying the adjacent flaps, and an ear portion projecting from each end of each intermediate rim section frictionally retained between the adjacent overlying and underlying rim portions.

6. A merchandising box formed from a single blank of paperboard material including, a bottom wall panel, a plurality of enclosing panels comprising alternate and intermediate panels hinged to said bottom wall panel, an inturned end tab hingedly connected to each end of alternate enclosing panels, an inturned rim section hingedly connected to each of said alternate panels providing an overlying rim portion and an underlying rim portion, a supporting portion hinged to each of said underlying rim portions abutting the inside face of the adjacent alternate panel for maintaining the overlying and underlying rim portions in substantial parallelism, each end of each overlying rim portion having a mitered end with the underlying rim portion projecting beyond said mitered ends, an inturned rim flap hinged to each of said end tabs supported upon the projecting end of the adjacent underlying rim portion and having a corner portion thereof inserted between the adjacent overlying and underlying rim portions, a rim section hinged to each of the intermediate panels overlying the adjacent flaps, and an ear portion projecting from each end of each intermediate rim section frictionally retained between the adjacent overlying and underlying rim portions.

7. A merchandising box including, a bottom wall panel, a plurality of enclosing panels comprising alternate and intermediate panels hinged to said bottom wall panel, an inturned rim section hingedly connected to each of said alternate panels providing an overlying rim portion and an underlying rim portion, a supporting portion hinged to each of said underlying rim portions abutting the adjacent inside face of the adjacent alternate panel and having its lower edge resting upon said bottom wall panel for maintaining the overlying and underlying rim portions in substantial parallelism, each end of each overlying rim portion having a mitered end with the underlying rim portion projecting beyond said mitered ends, a rim section hinged to each of the intermediate panels supported by the projecting ends of the underlying rim portions, and an ear portion connected to each end of each intermediate rim section frictionally retained between the adjacent overlying and underlying rim portions.

8. A prepared blank formed from a single sheet of paperboard material adapted to be assembled into a rigid box by interlocking parts of the blank including, a bottom wall panel, a plurality of enclosing panels comprising alternate and intermediate panels hinged to said bottom wall panel, a rim section hinged to each of said alternate panels, each alternate rim section comprising an outer rim portion hinged to an inner rim portion and adapted to be folded to underlie its associated inner rim portion, said outer rim portion having an ear portion at each end thereof extending beyond the adjacent end of its associated inner rim portion, a rim section hinged to each of said intermediate panels having a locking ear projecting from each end thereof, an end tab hinged to each end of said alternate panels, and a rim flap hinged to each of said end tabs.

9. A prepared blank formed from a single sheet of paperboard material adapted to be assembled into a rigid box form solely by interlocking paperboard parts of the blank without the use of applied securing means including, a bottom wall panel, a plurality of enclosing panels comprising alternate and intermediate panels hinged to said bottom wall panel, a rim section hinged to each of said alternate panels each comprising hingedly connected overlying and underlying rim portions, each of said overlying rim portions having its ends cut on a miter with the ends of the underlying rim portion projecting beyond the mitered ends of the overlying rim portion, an end tab hinged to each end of each alternate panel, a rim flap hinged to each of said end tabs, having a corner portion adapted to be inserted between adjacent overlying and underlying rim portions when the box is erected, and a rim section hinged to each of said intermediate panels having a locking ear at each end thereof adapted to be inserted between adjacent overlying and underlying rim portions when the box is erected.

10. A merchandising box including, a bottom wall panel, a plurality of enclosing panels comprising alternate and intermediate panels hinged to said bottom wall panel, an inturned rim section hinged to each of said alternate panels providing an overlying rim portion and an underlying rim portion, means for retaining the overlying and underlying rim portions in substantial parallelism, an inturned end tab hinged to each end of said alternate panels, an inturned

rim flap hinged to each of said tabs, each of said rim flaps having a corner portion frictionally retained between adjacent overlying and underlying rim portions, inturned rim section hinged to each of said intermediate panels, an ear projecting from each end of each intermediate rim section frictionally retained between adjacent overlying and underlying rim portions, and a locking flap hinged to each of said intermediate rim sections enclosing the aligned inner edges of adjacent rim flaps.

11. A merchandising box formed from a single blank of paperboard material including, a bottom wall panel, a plurality of enclosing panels comprising alternate and intermediate panels hinged to said bottom wall panel, an inturned rim section hinged to each of said alternate panels providing an overlying rim portion and an underlying rim portion, an inturned end tab hinged to each end of each alternate panel, an inturned rim flap hinged to each of said tabs, a rim section hinged to each of said intermediate panels, an ear projecting from each end of each intermediate rim section frictionally retained between adjacent overlying and underlying rim portions, a locking flap hinged to each of said intermediate rim sections folded to enclose the aligned inner edges of the adjacent rim flaps, and an inturned cover-supporting portion underlying each of said locking flaps.

12. A merchandising box including, a bottom wall panel, a plurality of enclosing panels comprising alternate and intermediate panels hinged to said bottom wall panel, an inturned double-ply rim section hingedly connected to each of said alternate panels, corner portions comprising hingedly connected bellows fold sections connecting the adjacent ends of adjacent alternate and intermediate panels with the bellows fold section hinged to the alternate panel having an inturned rim flap, each of said rim flaps having a corner portion thereof inserted between the plies of the adjacent double-ply rim section, a rim section hinged to each of said intermediate panels, and an ear projecting from each end of each intermediate rim section adapted to be frictionally retained between the plies of the adjacent double-ply rim section.

13. A merchandising box formed from paperboard material including, a bottom wall panel, a plurality of enclosing panels comprising alternate and intermediate panels hinged to said bottom wall panel, a rigid reinforcing frame supported by said bottom wall panel positioned within said enclosing panels, an inturned end tab hinged to each end of each alternate panel, an inturned rim flap hinged to each of said tabs, and an inturned double-ply rim section hinged to each of said alternate panels overlying the top edge of said frame, each of said rim flaps having a corner portion thereof inserted between the plies of the adjacent double-ply rim sections, a rim section hinged to each of said intermediate panels folded over adjacent aligned rim flaps and the top edge of said frame, and inter-engaging means comprising parts of said rim sections for retaining said box in fixed assembled position.

14. A merchandising box formed from a single blank of paperboard material including, a bottom wall panel, a plurality of enclosing panels comprising alternate and intermediate panels hinged to said bottom wall panel, a rigid reinforcing frame supported by said bottom wall panel positioned within said enclosing panels,

each of said alternate panels having an inturned double-ply rim forming section comprising an overlying rim portion and an underlying rim portion resting on the top edge of said frame, a double-ply rim section hinged to each of said intermediate panels comprising an overlying rim portion and an underlying rim portion resting on the top edge of said frame, said intermediate overlying rim portion having an ear projecting from each end thereof inserted between the adjacent alternate overlying and underlying rim portions for retaining said enclosing panels and rim sections in fixed assembled position.

15. A merchandising box formed from a single blank of paperboard material including, a bottom wall panel, a plurality of enclosing panels comprising alternate and intermediate panels hinged to said bottom wall panel, a rigid reinforcing frame supported by said bottom wall panel and positioned within said enclosing pan-

els, an inturned rim section hinged to each of said alternate panels comprising an overlying rim portion and an underlying rim portion resting upon the top edge of said frame whereby the overlying and underlying rim portions are retained in substantial parallelism, an inturned end tab hinged to each end of said alternate panels positioned adjacent the outer surface of said frame, an inturned rim flap hinged to each of said tabs and resting on the top edge of said frame, an inturned rim section comprising an overlying rim portion hinged to each of said intermediate panels and an outturned underlying rim portion resting on the top edge of said frame, and an ear projecting from each end of each intermediate section frictionally retained between adjacent overlying and underlying rim portions of the adjacent alternate rim section.

WILLIAM A. RINGLER.
